UNITED STATES PATENT OFFICE

DONALD McLELLAN, OF WOODSTOCK, ONTARIO, CANADA.

MOP-HEAD.

SPECIFICATION forming part of Letters Patent No. 325,261, dated September 1, 1885.

Application filed October 11, 1884. (Model.) Patented in Canada February 11, 1885, No. 21,071.

To all whom it may concern:

Be it known that I, DONALD McLELLAN, a subject of the Queen of Great Britain, residing at Woodstock, in the county of Oxford and Province of Ontario, Canada, have invented a certain new and useful Improvement in Mop-Heads, of which the following is a specification.

My invention relates to improvements in mop-heads; and its objects are, first, to facilitate the insertion and removal of the mopping material; second, to secure the material firmly in position, and, third, to accomplish these ends with simplicity of structure. I attain these objects by the device illustrated in the accompanying drawings, in which—

Figure 1 is a front view of a mop-head embodying my invention. Fig. 2 is a detached view of the curved wire lever. Fig. 3 is a side view of the mop-head, and Fig. 4 is a front view thereof having the spring removed.

Similar designations indicate corresponding parts in the views.

To an ordinary handle, A, a hollow cap, H,

is secured by any means, as by a nail or pin, 25 K. This cap is pyramidal in shape, and has a hook, G, and an arm, M, which terminates in a grooved cross-head, B' C'. Lugs f f also project radially from this cap near its base. Upon inserting suitable mopping material in 30 the space L N and passing the curved wire spring B C D E thereover, so that the hole G' will receive the hook G, and passing the legs D E over the lugs f f, said material will be firmly held, and can easily be replaced when 35 worn.

What I claim is—

In a mop-head, the tapering cap H, provided with a hook, G, and grooved cross-head B' C', in combination with the wire B C D E, curved 40 as shown and described, pins f f, radially projecting from said cap near its base, and handle A, for the purpose set forth.

DONALD McLELLAN.
